UNITED STATES PATENT OFFICE

109,442

DESIGN FOR A DRESS ENSEMBLE

Samuel Chapman, New York, N. Y.

Application March 17, 1938, Serial No. 75,888

Term of patent 3½ years

To all whom it may concern:

Be it known that I, Samuel Chapman, a citizen of the United States of America, residing in city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view thereof.

Fig. 3 is a front view of the dress member of the ensemble.

Fig. 4 is a rear view of Figure 3.

The characteristic feature of my design resides in the combination on the ensemble disclosed of the specific jacket which features rosettes applied over the entire surface of the jacket as shown in combination with the specific dress as shown.

I claim:

The ornamental design for a dress ensemble substantially as shown and described.

SAMUEL CHAPMAN.
